(57) **CLAIM**

The ornamental design for an engine mount for a work vehicle, substantially as shown and described.

DESCRIPTION

FIG. 1 is a perspective view of an engine mount for a work vehicle;

FIG. 2 is a front view of the engine mount for a work vehicle;

FIG. 3 is a back view of the engine mount for a work vehicle;

FIG. 4 is right side view of the engine mount for a work vehicle;

FIG. 5 is a left side view of the engine mount for a work vehicle;

FIG. 6 is a top view of the engine mount for a work vehicle; and,

FIG. 7 is a bottom view of the engine mount for a work vehicle.

In the drawings, the broken lines depict unclaimed subject matter only and form no part of the claimed design.

1 Claim, 4 Drawing Sheets
